UNITED STATES PATENT OFFICE.

LUCIEN H. DALLARD, OF NEW YORK, N. Y.

VICE.

1,340,477.

Specification of Letters Patent.

Patented May 18, 1920.

Application filed July 11, 1919. Serial No. 310,156.

To all whom it may concern:

Be it known that I, LUCIEN H. DALLARD, a citizen of France, and a resident of the city of New York, borough of Manhattan, 5 in the county and State of New York, have invented a new and Improved Vise, of which the following is a full, clear, and exact description.

This invention relates to new and useful 10 improvements in vises and it pertains more particularly to vises known as the quick adjusting type.

The primary object of the invention is to provide a mechanism by means of which the 15 jaws may be readily opened to any desired adjustment without the necessity of rotating the driving screw.

A further object of the invention is to provide a novel mechanism by which the 20 driving screw is disengaged from the operating mechanism.

With the above and other objects in view, reference is had to the accompanying drawings in which—

25 Figure 1 is a view partly in elevation and partly in section;

Fig. 2 is a vertical sectional view on the line 2—2 of Fig. 1;

Fig. 3 is a similar view showing the parts 30 in expanded position;

Fig. 4 is a detail view of the cam member;

Fig. 5 is a top plan view of the expandible nut in its expanded position.

Referring more particularly to the drawings, the reference character 6 designates 35 a bench or other suitable support, and suitably secured to said support is a track 7, the inner side walls of which are angularly disposed as designated by the reference character 40 8.

The reference character 9 designates the 45 vise base and said base has a projecting portion 10 having angular side walls adapted to engage the angular side walls 8 of the track 7 to provide means by which the vise is adjustable relatively to the track 7. The reference character 11 designates the stationary jaw, and 12 designates the movable jaw, both of said jaws being provided on 50 their gripping faces with hard metal inserts 13 commonly employed in devices of this character.

The movable jaw 12 is hollowed out as at 55 14, and mounted in said hollowed-out portion 14 is a yoke member 15, and said yoke member is secured against movement by

means of bolts 15' which pass through the base 9, as shown in Fig. 1. The yoke member 15 has two vertically-disposed arms 16, and said arms 16 are provided with alined 60 perforations 17, the purpose of which will be hereinafter described. Projecting inwardly and upwardly from the base of the yoke 15 are lugs 18, and pivotally mounted in said lugs 18 are levers 19, the upper ends 65 of which are pivotally connected as at 20, to beveled rings 21.

Extending through the movable jaw 12, is a rod 22, the inner end of which is screw threaded as designated by the reference 70 character 23, and slidably mounted with respect to the outer end of the rod 22, is an operating handle 24. The screw-threaded portion 23 of the rod 22 extends through the alined perforations of the vertically extending arms 16 of the yoke 15, and surrounding said screw-threaded portion 23 and positioned between the vertically-disposed arms 16 is a split nut, the two half sections of 75 which are designated by the reference characters 24 and 25. The half sections 24 and 25 of the split nut have oppositely-disposed beveled ends 26, and slidably mounted on said beveled ends 26 are the beveled rings 21 heretofore mentioned. Interposed between the half sections 24 and 25 of the split nut are coil springs 27, and said coil springs 27 serve to expand the half sections 24 and 25 so that they disengage from the screw-threaded portion 23 of the rod 22. The 90 lower ends of the levers 19 extend below their respective pivotal points, as designated by the reference character 28, and adapted for operation between the said ends 28 of the levers, is a cam member 29. This cam 95 member 29 is keyed to a shaft 30, as at 31, and said shaft 30 projects through the movable jaw 12, and is provided on its free end with an operating lever 32, by means of which said shaft is rotated.

Interposed between the lower ends 28 of the levers 19, is a spring 33, which is adapted to pull the lower ends of said levers together as the movement of the cam member 29 permits, which action slides the beveled rings 105 21 down the inclined ends 26 of the half sections 24 and 25 of the split nut, and permits an expansion of said nut under the influence of the coil springs 27.

The operation of the device is as follows: 110 When it is desired to adjust the movable jaw 12, the lever 32 is operated to rotate the

shaft 30, and upon rotation of the shaft 30, the narrow part 29' of the cam 29 is positioned between the lower ends 28 of the levers 19. Under the influence of the spring 33, the lower ends of these levers 19 are brought together, thus sliding the beveled rings 21 within the tapered ends 26 of the half sections 24 and 25 of the split nut. When the beveled rings 21 have assumed the position shown in Fig. 5, the springs 27 spread the half sections of the split nut as shown in Figs. 3 and 5, thus permitting of free movement of the threaded end 23 of the rod 22 through the split nut.

When it is desired to grip a piece of work inserted between the jaws, the lever 32 is operated to move the shaft 30 in the opposite direction, during which movement the broader portion 29'' of the cam 29 is positioned between the lower ends 28 of the levers 19, and this movement spreads the lower ends of said levers, causing the beveled rings 21 to ride up the tapered ends 26 of the half sections of the split nut, causing said split nut to grip the threaded end 23 of the rod 22, as shown in Figs. 1 and 2. If now the rod 22 be rotated through the medium of the operating handle 24, it will be seen

that by reason of engagement of the screw-threaded portion 23 of the rod 22 with the split nut as heretofore described, the movable jaw 12 will be so moved as to cause it to grip the work between it and the stationary jaw 11.

Having thus described my invention, what is claimed as new is:

A device comprising a base, a stationary jaw, an adjustable jaw, a yoke carried by said base and provided with perforated arms, a threaded rod carried by the adjustable jaw and passing through the perforations on the arms of said yoke, a split elongated nut having tapered ends adapted to engage and disengage said rod, a plurality of springs carried by the half sections of said elongated split nut for spreading the nut out of engagement with said threaded rod, a plurality of rings adapted to move over the tapered ends of said split nut to cause the same to grip the threaded rod, and a swinging cam member adapted to operate said rings to cause engagement of the split nut with the threaded rod, substantially as described.

LUCIEN H. DALLARD.
